UNITED STATES PATENT OFFICE.

JOHN A. ROBERTSON, OF ST. JOSEPH, MISSOURI.

CABLE CLAMP.

Application filed April 7, 1922. Serial No. 550,301.

To all whom it may concern:

Be it known that I, JOHN A. ROBERTSON, a citizen of the United States, residing at St. Joseph, in the county of Buchanan and

5 State of Missouri, have invented certain new and useful Improvements in a Cable Clamp, of which the following is a specification.

My said invention relates to a cable clamp intended primarily for use in supporting 10 telephone cables in elevator shafts. Such a cable is vertically located in an elevator shaft and is supported by a steel rope or cable standing alongside thereof which is called a "messenger." In ordinary practice 15 the cable is attached to the "messenger" by wrapping wire about the cable and through the strands of the "messenger." The weight of the cable is very great and therefor such attachments must be made at intervals of 20 five or ten feet along the same. This work must be done before the cable is raised and even then there is a tendency to choke the cable. By the use of my device such difficulty is obviated and it becomes a relatively 25 simple matter to connect or disconnect the cable from the "messenger."

My device is also useful in drawing cables through conduits and manholes in underground cable work as it renders such 30 work easier and quicker.

Referring to the accompanying drawings which are made a part hereof and on which similar reference characters indicate similar parts,

35 Figure 1 is a side elevation of my device,

Figure 2 a similar elevation taken from the opposite side,

Figure 3 a section on line 3—3 of Figures 1 and 2 showing the clamp in closed 40 position,

Figure 3^a a similar section showing the clamp in open position, and

Figure 4 shows the underside of the upper clamp member.

45 In the drawings reference character 10 indicates a lower clamping member with which an upper clamping member 11 cooperates to grip the cable 12 therebetween. For connecting the clamping members I have provided a series of links 12 at each side thereof, the links being connected to lower member 10 by oppositely located screws 13 or by a set of bolts extending through the member and each supporting a 50 pair of links. At the upper end the links are connected to the upper clamp member

by bolts 14 each having a head 15 at one end and the other end being headless to permit the corresponding link to be readily slipped on and off. In this way the clamp may be 60 quickly opened or closed, the link at the other side having loose connection with bolts 13 and 14 to form a sort of hinge. Between the clamp members is a groove 18 here shown as comprising a smooth portion in 65 the lower member and a corrugated portion in the upper member.

The upper clamp carries an eye-bolt 19 extending upwardly therefrom and the lower member, an eye-bolt 20 located forwardly of the front end of member 11. A link composed of still another eye-bolt 21 connects the bolts 19 and 20 and a nut 22 on this link spaced from bolt 19 by a washer 23 limits the relative longitudinal movement 75 of the members 10 and 11 for opening the clamp but permits free relative movement in the direction for closing the same.

The end of the member 10 at which bolt 20 is located will be the upper end of the 80 clamp in use and the pivot 24 is located at this end. This pivot forms the pin of a clevis 25 which serves to connect a link 26 to the clamp. This link may be the end link of a chain connecting the clamp to the "messenger" or it may be connected to the "messenger."

In the use of my device the links at one side will be disconnected from the bolts 14 as shown in Figure 3^a and the upper member swung to one side to open the clamp. After placing the cable therein the clamp may be closed as in Figure 3. When the lifting operation begins and the strain of the cable falls on the clamp the part 11 will 90 move longitudinally relatively to the part 10 as shown in Figure 1 and thus will clamp the cable with increasing force dependent on the weight of the cable. As the clamp is in contact with the cable through the entire 95 length of the member 11 there is no choking or pinching action but an evenly distributed pressure.

It will be obvious to those skilled in the art that my device may be modified in various ways without departing from the spirit of my invention, the true scope of which is indicated in the appended claims.

Having thus fully described my said invention, what I claim as new and desire to 110 secure by Letters Patent, is:

1. A clamp comprising a pair of aligned

members adapted to move longitudinally in opposite directions to clamp a cable or the like between them and means connecting the members at one side to permit hinge-like opening of the clamp, substantially as set forth.

2. A clamp comprising a pair of alined members, links at opposite sides thereof permitting relative longitudinal movement between said alined members, a link extending longitudinally of said members and connections between said link and said members adapted to limit such relative longitudinal movement in one direction, substantially as set forth.

3. A clamp comprising a pair of alined members, a plurality of spaced links connecting the alined members, and means to stop their relative longitudinal movement in one directon approximately at the time of greatest separation between them, substantially as set forth.

4. A clamp comprising a pair of alined members, links at opposite sides thereof permitting relative longitudinal movement between said alined members, fixed abutments on said members, means secured to one abutment and adapted to bear against the other when the members are at the point of greatest separation to stop their relative longitudinal movement, substantially as set forth.

5. A clamp comprising a pair of alined members, links at opposite sides therof per-

mitting relative longitudinal movement between said alined members, pins projecting laterally from each member, links loosely connecting said pins and the pins along one side of a member being headless to permit quick detachment of the corresponding links for opening the clamp, substantially as set forth.

6. A clamp comprising a pair of alined members adapted to move longitudinally in opposite directions to clamp a cable or the like between them, and a bolt and link connection for the members permitting separation thereof along one edge to open the clamp, substantially as set forth.

7. A clamp comprising a pair of alined members adapted to move longitudinally in opposite directions to clamp a cable or the like between them, a bolt through the upper member, a bolt through the lower member, a link connecting said bolts at opposite sides of the clamp, said connection permitting separation of the members along one edge to open the clamp, substantially as set forth.

In witness whereof, I have hereunto set my hand and seal at St. Joseph, Missouri this 1st day of April, A. D. nineteen hundred and twenty-two.

JOHN A. ROBERTSON [L. s.]
